UNITED STATES PATENT OFFICE

160,725

COMBINATION CRACKER AND CONDIMENTS TRAY OR SIMILAR ARTICLE

Salvatore J. Manno, New York, N. Y.

Application June 10, 1949, Serial No. 3,198

Term of patent 3½ years

(Cl. D44—10)

To all whom it may concern:

Be it known that I, Salvatore J. Manno, a citizen of the United States of America, residing in the Borough of Manhattan, city of New York, county of New York, and State of New York, have invented a new, original, and ornamental Design for a Combination Cracker and Condiment Tray or Similar Article, of which the following is a specification, reference being had to the accompanying drawing, forming part thereof.

Fig. 1 is a plan view of a combination cracker and condiment tray, showing my new design;

Fig. 2 is a perspective view;

Fig. 3 is a bottom plan view;

Fig. 4 is a front elevational view thereof.

I claim:

The ornamental design for a combination cracker and condiment tray or similar article, as shown.

SALVATORE J. MANNO.
